APPARATUS FOR MAKING
PERFORATED BRICKS**

Walter J. Thomas, Sr., Plymouth Meeting, Pa., assignor, by mesne assignments, to International Minerals & Chemical Corporation, Skokie, Ill., a corporation of New York

Filed Dec. 28, 1965, Ser. No. 516,888
4 Claims. (Cl. 25—90)

ABSTRACT OF THE DISCLOSURE

An attachment for perforating bricks is employed with a conventional brick press and includes a power means, rocker arm and piercing means. A bracket is releasably secured to the upper portion of the press and the rocker arm is pivoted intermediately thereto. Power means is secured to one end of the rocker arm and the other end operates the piercing means. The piercing means operates through a bore in a bolt which secures the plunger to the plunger plate.

The present invention relates to a new and novel apparatus for making perforated bricks, and more particularly to a hole making attachment which can be incorporated with relatively conventional brick press mechanism.

The present invention represents an improvement over a conventional brick press of the type known as the Boyd press such as shown in United States Patent No. 987,124. In this type of press, upper and lower die means are employed between which material is compressed, the material being compressed within a mold means so as to form a finished brick of desired configuration.

The arrangement of the present invention provides an attachment which can be readily incorporated with this type of brick press and includes different forms adapted to perforate the finished brick to provide a hole either completely therethrough or only partly therethrough as desired. A particular advantage of the structure of the present invention is the fact that the attachment means may be employed by making only minor modifications to the conventional brick press structure.

The various components of each embodiment of the present invention may be readily secured to certain portions of the brick press, and the piercing means of the present invention is supported and guided in a unique manner. The upper plunger plate is ordinarily supported from the upper plunger by means of a pair of spaced bolts. In one form of the present invention, one of these bolts is provided with a bore therethrough, and the piercing means is slidably supported within the bore in such bolt. An aligned hole is provided in the associated die plate so that the piercing means can reciprocate with respect to the upper die plate into and out of operative position. In this manner, the upper bolt means serves a dual function in supporting the upper plunger plate and upper die plate on the upper plunger and additionally as a guide bushing for the piercing means.

The lower bolts which hold the lower plunger plate and lower die plate to the lower plunger are also employed in the conventional manner, and one of these bolts is additionally provided with a bore in alignment with the bore in the upper bolt. The lower die plate is provided with a hole in alignment with the bore in the associated lower bolt, and this latter hole and aligned bore serve as a means to relieve the pressure and excess material ahead of the piercing means as it moves downwardly through the material being pressed between the upper and lower die plates within the mold means.

The piercing means is operated by a power operated mechanism which is automatically controlled by the oper-

2

ation of the brick press so that the piercing means will be moved in timed relationship to the normal operation of the press.

In the second form of the invention, the upper plunger is provided with a hole which has disposed therewithin a bearing means with a bore formed therethrough. The piercing means is slidably positioned within this bearing means and is adapted to pass through an aligned hole formed in the upper die plate. As in the other form of the invention, the power operated mechanism is supported by the upper portion of the apparatus and is movable therewith and operated in timed relationship to the normal operation of the press.

An object of the present invention is to provide a new and novel apparatus for making perforated bricks.

Another object of the invention is the provision of apparatus for making perforated bricks including an arrangement which may be readily attached to an existing brick press.

Still another object of the invention is to provide apparatus for making perforated bricks wherein the bolt means employed for holding certain components together serves a dual function, firstly to serve as a guide means for the piercing means, and secondly to provide a means for relieving pressure and excess material ahead of the piercing means during operation of the apparatus.

Yet another object of the invention is to provide apparatus for making perforated bricks which is quite simple and inexpensive in construction, and yet which is quite efficient and reliable in use.

Other objects and many attendant advantages of the invention will become more apparent when considered in connection with the specification and accompanying drawings, wherein:

FIG. 1 is a top perspective view of the apparatus of the present invention;

FIG. 2 is a side view of the apparatus shown in FIG. 1 with certain parts broken away for the sake of clarity;

FIG. 3 is a sectional view taken substantially along line 3—3 of FIG. 2 looking in the direction of the arrows;

FIG. 4 is a sectional view taken substantially along line 4—4 of FIG. 2 looking in the direction of the arrows;

FIG. 5 is a schematic illustration of the control system for controlling the actuation of the power operating means of the hole making means;

FIG. 6 is a top perspective view of a finished brick as manufactured with the apparatus of the present invention;

FIG. 7 is a side view of a modification of the present invention with certain parts broken away and in section for the sake of illustration;

FIG. 8 is a sectional view taken substantially along line 8—8 of FIG. 7 looking in the direction of the arrows; and

FIG. 9 is an end view of the apparatus shown in FIG. 7 with certain parts thereof broken away and in section to illustrate the details of construction thereof.

Referring now to the drawings wherein like reference characters designate corresponding parts throughout the several views, a first form of the invention is shown in FIGS. 1—5 inclusive, wherein the crosshead of a generally conventional brick press is indicated by reference numeral 10, this crosshead being adapted to reciprocate in a vertical direction in the usual manner. The upper plunger is indicated by reference numeral 12 and defines a pair of cavities 14 and 16 at the opposite ends thereof. A pair of bolts 18 and 20 extend upwardly through suitable holes provided in the top portion of the upper plunger and are threaded into corresponding threaded holes formed in the crosshead. In this manner, the upper plunger is supported on the crosshead.

The upper plunger plate is indicated by reference nu-

meral 24 and the upper die plate is indicated by reference numeral 26, the die plate being supported from the plunger plate by means of screws or the like 28 extending through suitable holes provided in the plunger plate and being threaded into corresponding threaded holes provided in the die plate.

The upper plunger plate 24 is secured to the upper plunger 12 by means of a pair of bolts 32, each of these bolts being threaded downwardly through aligned threaded openings provided in the upper plunger and the upper plunger plate. As seen most clearly in FIG. 3, bolt 32 is provided with a central cylindrical bore 34 formed therethrough, and die plate 26 is provided with a hole 36 in alignment with the bore 34.

A lower plunger 40 may be of substantially the same construction as the upper plunger 12, and a lower plunger plate 42 and lower die plate 44 may be of the same construction as the corresponding members 24 and 26 respectively. The lower die plate 44 is secured to the lower plunger plate 42 by means of screws 46 which extend through suitable holes provided in the lower plunger plate and are threaded into correspondingly threaded holes provided in the lower die plate.

The lower plunger plate is secured to the lower plunger 40 by means of a pair of bolts 48 and 50 which are threaded through aligned threaded openings provided in these two members. Bolt 50 is provided with a substantially cylindrical bore 52 extending therethrough, and die plate 44 is provided with a hole 54 in alignment with bore 52 for a purpose hereinafter described.

The upper and lower portions described hereinabove are adapted to cooperate with a mold means, and as seen in FIG. 3, an opposite pair of mold walls 58 and 60 are illustrated, it being understood that the mold means provides a cavity closed on all sides of a suitable shape to provide the desired finished configuration to the manufactured brick. As seen in FIG. 3, a body of material 62 is being compressed between the upper and lower die plates within the mold means.

The hole making attachment means of the present invention includes a piercing means indicated generally by reference numeral 70, this piercing means as seen in FIG. 3 including a generally cylindrical upper portion 72 which snugly and slidably fits within the bore 34 in bolt 32 as well as the hole 36 in the die plate 26. The outer surface of the lower portion 74 of the piercing means is tapered downwardly toward the lower end thereof. The upper end of the piercing means is threaded as indicated at 76 and is threaded into a correspondingly threaded hole provided in the lower enlarged portion of a link member 78. A pin 80 extends through suitable holes provided in link 78 and the upper end of the piercing means to retain these members in operative relationship with respect to one another.

A bar member 84 extends between spaced portions at one end of the upper plunger 12 as seen most clearly in FIG. 1 and is secured in place by a pair of screws 86 which extend through suitable holes provided in the bar member and are threaded into correspondingly threaded holes in the upper plunger. A bracket member 88 is secured as by welding or the like to the bar member and extends outwardly therefrom and includes a pair of spaced depending arms 90 and 92.

As seen most clearly in FIG. 4, an operating arm 94 is provided, this operating arm being pivotally supported from the bracket 88 by means of a pivot pin 95 extending through suitable holes provided in arms 90 and 92 of the bracket as well as an aligned hole in the operating arm and being retained in operative position by a pin 96. One end of the operating arm is bifurcated to provide a pair of spaced longitudinally extending portions 98, and the opposite end of the operating arm is bifurcated to provide a pair of spaced longitudinally extending portions 100. Longitudinally extending slots 102 are provided in each of the portions 98, and similar longi-

tudinally extending slots 104 are provided in each of the longitudinally extending portions 100.

A pivot pin 110 extends through a hole provided in the upper end of link 78, pivot pin 110 being retained in operative position by a pin 112. It will be noted that the opposite ends of pin 110 are slidably positioned within the slots 102 so that the link 78 is effectively pivotally interconnected with one end of the operating arm and is adapted to move upwardly and downwardly in response to pivotal movement of the operating arm.

As seen most clearly in FIG. 1, an attaching plate is indicated by reference numeral 120, this attaching plate being generally T-shaped in configuration and being secured to the crosshead 10 by a pair of screws 112.

Power operated actuating means for the hole making attachment means comprises a pneumatic cylinder 124 of conventional construction, this pneumatic cylinder being supported on plate 120 by a plurality of screws 126. Conduits 128 and 130 are connected with opposite ends of the pneumatic cylinder and are interconnected with a source of gas under pressure as hereinafter described.

A piston rod 134 extends outwardly of the pneumatic cylinder 124, it being understood that a conventional piston is slidably positioned within the cylinder. A member 136 is connected with the lower end of the piston rod, the reduced lower portion of member 136 fitting between the portions 100 of the operating arm.

A pin 138 extends through a suitable hole provided in the lower end of member 136, pivot pin 138 being retained in operative position by a pin 140. It will be noted that the opposite ends of pin 138 are slidably positioned within the slots 104 in portions 100 of the operating arm, and in this manner the power operated actuating means is pivotally interconnected with the associated end of the operating arm.

Referring now to FIG. 5, the conduit means 128 and 130 are connected with a pair of solenoid valves 150 and 152 respectively. These solenoid valves are in turn connected with conduit portions 154 and 156 respectively which are interconnected with a conduit 158 which is in turn connected with a suitable source of air or the like under pressure sufficient to operate the pneumatic power operating means.

The two solenoid valves 150 and 152 are connected in a suitable electrical circuit for operating the solenoid valves at the proper time. Solenoid valves 150 and 152 are grounded by leads 160 and 162 respectively. An electrical lead 164 connected with solenoid valve 150 is in turn connected with a switch 166 adapted to connect or disconnect lead 164 with a lead 168 which in turn is connected with a suitable source of electrical energy. Solenoid valve 152 is connected by lead 170 with a switch 172 which is adapted to connect or disconnect lead 170 with a lead 174 which is also connected with a suitable source of electrical energy.

Switches 166 and 172 are controlled by timing cams 176 and 178 which are fixed for rotation with a portion 180 which may comprise a horizontal axial extension of the main press shaft or crankshaft. This interconnection may be similar to that shown in U.S. Patent No. 2,455,-823 wherein the rotary cam member of the timing switch is fixed upon a horizontal axial extension of the main press shaft or crankshaft. With this arrangement, the operation of the solenoid operated valves 150 and 152 is coordinated in timed relationship with the movement of the crossheads and plungers connected thereto.

It is evident from an inspection of FIG. 5 that when solenoid valve 150 is energized to permit air under pressure to enter the top of pneumatic cylinder 124, the piston rod 134 thereof will move downwardly. The solenoid valves 150 and 152 are provided with vents 150' and 152', and when the aforescribed movement of piston rod 134 downwardly occurs, the vent means 152' will be open to permit the air in the lower part of the cylinder to escape. It is apparent that when it is desired to again

raise the piston rod 134, the operation of the solenoid valves 150 and 152 will be reversed.

Referring now to FIG. 6, a completed brick according to the present invention is illustrated, the brick being indicated by reference numeral 184 and being in this instance of generally rectangular shape. It will be understood that the brick can have any suitable desired configuration. The finished brick will be provided with a hole 186 extending completely therethrough. This hole may be put in either a straight brick as shown or a key brick. When the hole is put in a key brick, it will always be put in the large end thereof.

In the operation of the apparatus and in carrying out the method of the present invention, assuming the upper portion of the apparatus to be in its uppermost position, the piston rod 134 will be in its lowermost position as indicated in phantom lines in FIG. 2 so that the operating arm will be in position to raise the piercing means to retract the piercing means slidably through the bore 34 and hole 36 in the bolt 32 and die plate 26 respectively.

As the upper crosshead moves downwardly carrying the plunger, the plunger plate and the die plate move downwardly therewith, and the operating arm is moved into the full line position as shown in FIG. 2 to extend the piercing means to its maximum extent beneath the upper die plate just before it enters the mold cavity. The piercing means remains in this extended position as the material within the mold cavity is compressed between the upper and lower die plates, and the bore 52 in the lower bolt 50 and the hole 54 in the lower die plate 44 serve to relieve the pressure and excess material ahead of the piercing means as it moves downwardly through the material within the mold means.

The piercing means is again retracted by moving the operating arm 94 into the phantom line position shown in FIG. 2 just before the finished brick is removed from the mold cavity and while pressure is still being applied to the finished brick. The die plates are then moved apart and the completed brick is removed from the mold to provide the finished configuration shown in FIG. 6.

Referring now to FIGS. 7-9 inclusive, a modification of the invention is illustrated. The crosshead of the brick press is indicated by reference numeral 200 and is adapted to reciprocate in a vertical direction. The upper plunger is indicated by reference numeral 202, this upper plunger being secured to the crosshead by a pair of similar bolts 204 which extend upwardly through suitable holes provided in a skirt portion 206 and are threaded into correspondingly threaded holes formed in the crosshead.

The upper die plate is indicated by reference numeral 210, and the upper plunger 202 is provided with a pair of spaced cutout portions 214. A pair of similar bolts 216 are threaded downwardly through correspondingly threaded aligned holes provided in the upper plunger and in the die plate for securing the upper plunger and the upper die plate in the operative position illustrated.

A lower die plate 220 is provided, this lower die plate being mounted on a suitable lower plunger which may be similar to the upper plunger 202. It will be understood that the upper and lower portions including the upper and lower die plates are adapted to cooperate with the mold means in the same manner as discussed in connection with the previous modification, and no further discussion or illustration of this feature is considered necessary in connection with the modification shown in FIGS. 7-9 inclusive.

The piercing means of this form of the invention is illustrated generally by reference numeral 230, the piercing means having an outer surface on the lower portion 232 thereof which tapers downwardly toward the lower end of the piercing means. The piercing means is illustrated in its lowermost limit of movement in FIG. 7, and it will be apparent that with the die means at their limits of movement as illustrated, the piercing means will form a perforation only part way through the completed brick.

The upper end 234 of the piercing means is threaded into a correspondingly threaded hole provided in a slideable member 236. This member 236 is mounted for sliding movement within a hole 238 formed vertically within the upper plunger 202. A hole 240 is provided in the upper die plate 210, and a hole 242 is provided in the skirt portion 206, the latter two holes being generally in alignment with the hole 238 formed in the upper plunger. The hole 238 opens through the right side of plunger 202 as seen in FIG. 7 to provide an elongated slot therein, and the hole is further provided with a slightly enlarged portion as seen in FIG. 7 opposite to the slot formed in the side of the plunger.

A bearing means 246 is press-fitted within the lower portion of the hole formed in the upper plunger and within an enlarged counterbored portion of the hole 240 in the upper die plate 210. The main cylindrical body portion of the piercing means 230 is slidably positioned within a longitudinally extending bore provided in bearing member 246 whereby the piercing means is guided and supported during vertical reciprocation thereof. The slideable member 236 is provided with a recessed portion 250 therewith including sloping cutout portions 252 and 254 for a purpose hereinafter described. The recess 250 is adapted to receive the rounded end portion 260 of an operating arm 262. The cutout portions 252 and 254 provide clearance with the operating arm 262 at the opposite limits of its movement. The outer end of operating arm 262 is secured to a shaft 264 for rotation therewith. As seen in FIG. 9, a jam nut and washer assembly 266 is provided on a threaded reduced end portion 268 of shaft 264 for holding the outer end of operating arm 262 in operative position.

A bracket support member 272 is secured to the upper plunger 202 by a pair of bolts 274 passing through suitable openings provided in bracket 272 and being threaded into correspondingly threaded holes provided in the upper plunger. Bracket support 272 includes a member 276 having a bore formed therethrough which supports a pair of spaced bearings 278 which serve to support the shaft 264 for rotation with respect thereto.

A hollow housing member 280 is secured to the upper plunger by a pair of bolts 282 extending through suitable openings provided in the housing portion 280 and being threaded into correspondingly threaded holes provided in the upper plunger. It will be noted that this housing portion 280 normally serves to cover and protect the end of the shaft 264 and the associated portion of the operating arm 262.

As seen most clearly in FIG. 9, the left-hand end portion of shaft 264 is provided with a key 284, this portion of the shaft and the key being received within a correspondingly shaped hole provided in the end of a connecting link 286, the shaft and link being retained in their operative position shown by a set screw 288 threaded through a suitable hole provided in link 286 and engaging the shaft 264.

The upper end of link 286 is bifurcated to provide the two portions 290 which are pivotally interconnected with a male rod end 292 by a nut and bolt assembly indicated by reference numeral 294.

The rod end 292 is interconnected with the piston rod 300 which in turn is interconnected with the piston disposed within a conventional pneumatic cylinder 302. The cylinder 302 includes an attaching lug portion 304 which is pivotally interconnected with a bracket member 306 by a suitable pin 305.

Bracket 306 is supported by means of bolts 308 from a bracket 310 which in turn is supported by bolts 312 from an angle member 314 which is secured to the crosshead 200 by means of bolts 316.

The piercing means is shown in FIG. 7 in its lowermost extended position, and the remaining components are shown in a corresponding full line position. The phantom line position as seen in FIG. 7 illustrates the position of

the connecting link 286 and the associated components when the apparatus is in such a position to retract the piercing means so that it will be withdrawn through the hole in the upper die plate 210. It will be understood that the pneumatic cylinder 302 illustrated in this latter form of the invention may be operated by the same operating system as shown in FIG. 5 of the drawings so that the operation of the piercing means is carried out in timed relationship to the movement of the upper and lower portions of the brick press. It will of course be evident that the method carried out by the apparatus shown in FIGS. 7-9 inclusive will be the same as that previously described.

It is apparent from the foregoing that there is provided according to the present invention a new and novel method and apparatus for making perforated bricks. The arrangement of the present invention may be readily attached to an existing brick press. In one form of the invention, the upper bolt means provides the dual function of bolting the upper plunger and upper plunger plate together and at the same time serving as a guide bushing for the piercing means, while the lower bolt means serves the dual function of interconnecting the lower plunger and lower plunger plate and also to relieve the pressure and excess material ahead of the piercing means as it moves downwardly through the material in the mold cavity. In another form of the invention, a bearing means is provided for guiding sliding movement of the piercing means during vertical reciprocation thereof, this bearing means being press-fitted into suitable holes provided in the upper plunger and upper die plate. The apparatus of the present invention is quite simple and inexpensive in construction, and yet at the same time is quite efficient and reliable in operation.

As this invention may be embodied in several forms without departing from the spirit or essential characteristics thereof, the present embodiment is therefore illustrative and not restrictive, and since the scope of the invention is defined by the appended claims, all changes that fall within the metes and bounds of the claims or that form their functional as well as conjointly cooperative equivalents are therefore intended to be embraced by those claims.

What is claimed is:

1. Apparatus for making perforated bricks comprising an upper portion and a lower portion, said upper portion including an upper crosshead, an upper plunger secured

to said crosshead, an upper plunger plate, and an upper die plate with a hole therethrough, said upper plunger plate and said upper die plate being releasably interconnected with one another, bolt means securing said upper plunger plate to said upper plunger, said lower portion including a lower plunger, a lower plunger plate and a lower die plate, said lower plunger plate and said lower die plate being releasably interconnected with one another, bolt means securing said lower plunger plate to said lower plunger, mold means for receiving said upper and lower die plates to compress material between said die plates within said mold means, piercing means adapted to project through said upper die plate hole and between said mold means, said first mentioned bolt means having a bore formed therethrough for slidably receiving said piercing means, bracket means releasably secured to said upper portion, a rocker arm pivotally supported by said bracket means and having one end interconnected with said piercing means for moving said piercing means, power operating means releasably supported by said upper portion and operatively connected with the other end of said rocker arm for moving said piercing means with respect to said upper portion.

2. Apparatus as defined in claim 1 wherein the respective ends of the rocker arm are slotted and slidably receive the pivot pins carried by the respective piercing means and power means.

3. Apparatus as defined in claim 1, wherein said lower portion includes a hole in vertical alignment with said bore and upper die plate hole.

4. Apparatus as defined in claim 3, wherein said lower portion hole is partially defined by a bore formed through said second mentioned bolt means.
